ELECTRIC ARC FURNACE

Kurt Schneider and Hermann Schunck, Bitterfeld, Germany, assignors to I. G. Farbenindustrie Aktiengesellschaft, Frankfort-on-the-Main, Germany

Application January 23, 1937, Serial No. 121,988
In Germany January 28, 1936

1 Claim. (Cl. 13—11)

This invention relates to a method of and means for magnetically blowing electric arcs on metal electrodes.

When metal electrodes are employed in electric arc furnaces, it is necessary to cause the points where the arc is struck to migrate over the electrodes, in order to prevent them from fusing under the influence of the temperatures generated at the striking point. This migration 5 can be effected by blowing the arc, by means of a current of gas by mechanically moving, for example rotating, the electrodes or by generating in the proximity of the arc, a magnetic field energised by direct or alternating current. In 10 the last-named method however, the generating of said field by means such as electromagnets separated and remote from the electrodes themselves, entails, especially in the case of electric furnaces of the covered type, a corresponding 15 modification in the furnace design, in order to accommodate the electromagnets. This imposes limitations on the form of the furnace chamber which are frequently inconvenient or undesirable. On the other hand when the energising 20 coil is situated outside the shell of the furnace difficulties are encountered in adequately heat-insulating the shell.

The present invention aims at obviating the necessity of providing arc-blowing means separate from the electrodes and the disadvantages consequent thereon, by generating the electromagnetic blowing field in the electrode itself by means of an electric current circulating round or 25 passing through the electrode.

This arrangement, in which the means energising the magnetic field from an integral unit with the electrode, does not in any way interfere with the normal furnace design. For example, in the case of shaft furnaces, the shell may be 30 provided with heat-insulating layers of any convenient thickness, or in the case of drum furnaces, which are particularly favoured in view of their thermal economy, such furnaces may be equipped with metal electrodes, which was 35 hitherto considered impossible. Gas-reaction furnaces too, can be of particularly simple design, since the reaction chamber can be designed solely with a view to obtaining optimum conditions of flow in the gas space, without having 40 to take into consideration the restrictions otherwise imposed by the accommodation of the electromagnetic blowing means.

In order more clearly to understand the invention, reference is made to the accompanying

drawing which illustrates diagrammatically and by way of example an embodiment thereof.

The metal electrodes E_1 and E_2 are of the known hairpin design.

B and C denote respectively the in- and out-leads for the working current generating the arc L between the hairpin electrodes E_1 and E_2 , the path of said current being therefore from B to C via L. An auxiliary energising current, of 5 high strength and very low voltage indicated by U in the drawing, is generated in the annular conductor D, E, F, by any suitable source Q of 10 high intensity, low voltage direct or alternating current, which source is preferably located at the point of entry of the electrode into the 15 furnace chamber (i. e. between D and F'). This source may, in the case of direct current, be a thermo-element. This auxiliary current generates the magnetic field, represented by annular 20 arrows K surrounding the electrode E_1 .

This construction results in the lines of force of the electromagnetic field winding very closely round the electrodes and in said field therefore substantially retaining such a form as also to surround the electrodes at the striking point. 25

If different types of current be employed for the working and energising currents, i. e. direct current as working current and alternating current as energising current or vice versa, the arc will not be extinguished but will travel to and 30 fro on the electrode, the resulting arc being thus evenly distributed on both sides of the electrode. On the other hand, if direct current, or alternating current, be exclusively employed, the arc will assume the form of a stationary semi-circular 35 disc. In such case the current energising the electromagnetic field can be generated, in a particularly simple manner as shown in the drawing, in a transformer energised by the working current, and, if alternating current be 40 employed, the correct phase relation between the working current and the energising current is automatically obtained.

When heating solid or liquid substances disposed on the hearth of the furnace, for instance 45 when applying the invention to a horizontal drum furnace, and when the electrodes are arranged horizontally and either only direct, or only alternating, current is used, the semi-circular arc may be directed downwards and 50 may be caused to play directly on the charge material, whilst the ceiling of the furnace is thus protected. In such case, when the charge to be melted is a conductor, the arc is struck not only between the two electrodes, but also between 55

each electrode and the conducting charge material, whereby a particularly favourable utilisation of energy is assured.

In order to avoid extinction of the arc when operating solely with alternating current, alternating currents of different frequencies can be employed for the working current and for the energising current, provided that both frequencies are in integral proportion and that they have a series of zero points in common.

10 We claim:

An electric arc furnace comprising two oppos-

ing electrodes of hairpin design, means for supplying a working current through and across the gap between said electrodes, and separate means, appurtenant and adjacent to at least one of said electrodes for generating a current of high intensity and low voltage which is superimposed on the working current, traverses only its appurtenant electrode and generates a field consisting of a series of circular lines of force closely surrounding said electrode along its length.
